United States Patent Office

Des. 230,000
Patented Jan. 22, 1974

230,000

SHEET OR SIMILAR ARTICLE OF BED LINEN

Emeric Kanitz, Paris, France, assignor to Cannon
Mills Company, Kannapolis, N.C.

Filed May 13, 1971, Ser. No. 143,292

Term of patent 14 years

Int. Cl. D6—13

U.S. Cl. D6—264

FIG. I

FIG. 1 is a top plan view of a sheet showing my new design; and

FIG. 2 is an enlarged fragmentary top plan view thereof.

I claim:

The ornamental design for a sheet or similar article of bed linen, substantially as shown.
